UNITED STATES PATENT OFFICE.

JOHN ELDER, OF NEW YORK, N. Y., ASSIGNOR OF ONE-HALF TO ANNIE V. BRYAN, OF SAME PLACE.

SEWER-TRAP.

SPECIFICATION forming part of Letters Patent No. 624,773, dated May 9, 1899.

Application filed October 27, 1898. Serial No. 694,658. (No model.)

To all whom it may concern:

Be it known that I, JOHN ELDER, a citizen of the United States, residing in New York, (Corona,) in the county of Queens and State 5 of New York, have invented a new and useful Improvement in Sewer-Traps; and I do hereby declare that the following is a full, clear, and exact description of the same.

The main object of my invention is to provide an improved trap for drain-pipes having a valve which will automatically open to permit the waste water to escape into the sewer or other drain and will automatically and positively close, so as to effectually prevent 15 sewer-gas or waste water from backing up through the trap. I attain this and other important ends, briefly, by means of a trap having a valve operated by the water-supply and a float-valve which is operated by the 20 water passing through the trap, so as to control the operation of the waste-valve by the water-supply.

In order that my invention may be fully understood, I shall first describe in detail the 25 mode in which I carry the same into practice and then particularly point out the various features of the invention in the claims.

Reference is to be had to the accompanying drawings, forming part of this specification, 30 in which corresponding parts are designated by like letters throughout.

Figure 1 is a sectional elevation of a sewer-trap constructed in accordance with my invention. Fig. 2 is a sectional plan view of the 35 same. Fig. 2^a is a detailed view of a part of the same hereinafter described. Fig. 3 is a sectional elevation representing a modification of my invention. Fig. 4 is a reduced sectional view of part of the same.

40 The trap illustrated in Figs. 1 and 2 is formed with an inlet A, connected to the drain-pipe leading from the house, a U-bend B, which holds the water seal, an outlet C, which is connected to the sewer or street drain-pipe 45 C', a plugged cleaning-pipe D, a vertical plunger-chamber E, and an outlet F, which is protected by a strainer and is connected by a pipe H with a tank I, containing a valve-actuating float P.

50 At the junction of the bend B and waste-outlet C is formed a valve-seat K, which is

fitted to and normally closed by a valve L, so as to effectually prevent sewer-gas or waste water from backing up from the waste-pipe C' through the trap.

55 The valve L is carried by a tubular stem L', which is fitted to work vertically in the stuffing-box L² of a diaphragm L³, extending across the vertical plunger-chamber E above the waste-outlet C, and on the upper end of 60 the valve-stem L' is fixed a plunger M, fitted to work in the chamber E. The upper end of the chamber E being closed by a screw-plug E' the hollow stem L' of the valve permits the air to escape therethrough when the 65 plunger moves, and this prevents its being locked by the air.

Through the diaphragm L³ extend small escape-orifices L⁴, having simple flap-valves L⁵, which when the valve L is raised to its 70 fullest extent are pressed thereby against, so as to close the orifices L⁴ and prevent the water from escaping therethrough.

75 Into the chamber E above the diaphragm L³ leads a pipe N, which is connected to the main water-supply under pressure and which is normally closed by a valve O. The valve O has a sliding stem O' extending to the tank I into position to be operated by the head P' of the pivoted float P. The head P' forms 80 one arm of an angle-lever, to which the float P is adjustably secured by a set-screw and stem, as shown in Fig. 2^a, said angle-lever being pivoted to a fixed bracket and its upwardly-projecting arm pressing against the 85 valve-stem O' in a manner similar to that illustrated in Fig. 3 in connection with the float R. By this arrangement when waste water runs from the house into the bend B of the trap, the waste-valve L being closed, it (the waste 90 water) flows outward through the branch pipe into the tank I, thereby raising the float P, which in turn opens the supply-valve O. The water under supply-pressure then runs through the supply-pipe N into the chamber 95 E above the diaphragm L³ and, acting on the under side of the plunger M, positively raises the same, and thus the waste-valve L, and permits the waste water to escape from the trap into the waste-pipe C'. After the waste water 100 has run out it falls into the tank I, permitting the float P to fall and the supply-valve

to shut off the supply from the pipe N. The water in the chamber E above the diaphragm L³ then escapes through the orifices L⁴, washes the valve L, and causes the same to fall and close the trap against sewer-gas and back-water.

The modified form of my trap (shown in part in Figs. 3 and 4) is provided with means, substantially as shown in Figs. 1 and 2, for 10 positively opening the waste-valve L to permit the waste water to escape and, in addition thereto, with means for positively closing the valve L against backwater from the sewer. I accomplish this, briefly, by causing 15 the water backing up in the waste-pipe C' to operate a float-valve, which in turn causes the water-supply to close the waste-valve L.

As shown in Figs. 3 and 4, the waste-pipe C' opens into a float-tank Q, in which is a 20 pivoted float R, having an arm R' in operating connection with the stem S' of a double valve S. The valve S is arranged alternately to cut off the pipe N, which leads from the valve O into the plunger-chamber E, as shown 25 in Figs. 1 and 2, and another water-supply pipe T, which leads into the plunger-chamber E above the valve-actuating plunger M'. In the upper end of the tubular valve-stem L' is a spring-held valve U, which will be held open 30 by its spring to permit the air to escape when the plunger M' rises, but will be closed by the water under pressure coming from the supply-pipe T, and thereby cause said supply to depress the plunger M' and valve L. The 35 operation of this modified form of apparatus is as follows: When the waste water runs from the house into the trap, the valve L will be opened and the waste water permitted to escape as and by the means described in connection with Figs. 1 and 2, the double valve 40 S normally leaving the supply-pipe N open to be controlled by the valve O, as previously described. When, however, the water from the sewer or street-drain from any cause 45 backs up into the waste-pipe C', it enters the float-tank Q, raises the float R, and shifts the

valve S, so as to make it open the pipe T and close the pipe N. The pressure is therefore cut off from the plunger M' and admitted into the chamber E above said plunger, thereby 50 positively closing the waste-valve L and effectually preventing the water from backing up through the trap. When the waste-water float R falls again, the trap is set for operation by the float-valve O, as before described. 55

I claim as my invention—

1. A trap for drain-pipes comprising in combination a waste-valve, a plunger-chamber, a plunger therein connected to the waste-valve, a water-supply pipe leading into the 60 plunger-chamber a valve in the water-supply pipe, a waste-water tank connected to the trap, and a float in the tank to operate the supply-valve.

2. A trap for drain-pipes comprising in combination a waste-valve, a plunger-chamber, a plunger therein, a perforated diaphragm separating the plunger-chamber from the waste-valve, the valve-stem working through said diaphragm and carrying the plunger, a 70 water-supply pipe leading into the plunger-chamber, a valve in the water-supply pipe, a waste-water tank connected to the trap, and a float in said tank to operate the supply-valve. 75

3. A trap for drain-pipes comprising in combination a waste-valve, a plunger-chamber, a plunger therein connected to the waste-valve, water-supply pipes leading into the plunger-chamber on both sides of the plunger, valves to cut off both said supply-pipes, a waste-water tank connected to the trap, a back water-tank connected to the waste-pipe, and floats in said tanks to operate said valves alternately. 80 85

In testimony whereof I have hereunto set my hand the 16th day of July, 1898.

JOHN ELDER.

In presence of—

HENRY W. STROTHMANN,
JOHN LUTONACKRE.
